STOCKING SUSPENDER

Filed July 15, 1931

Inventor:
Wilhelm Greineisen.
W. Greineisen

UNITED STATES PATENT OFFICE

WILHELM GREINEISEN, OF BERLIN, GERMANY

STOCKING SUSPENDER

Application filed July 15, 1931, Serial No. 550,955, and in Germany November 22, 1930.

For securely holding stockings clamps are employed, which are attached by wide elastic bands to the corset or the like. The clamps consist of a metal loop and of a button which is arranged on a band portion attached to the metal loop. The attachment of the metal loop to the elastic band is effected by means of a metal strap, through which the elastic band is threaded, the portions of the elastic band being connected the one with the other by a metal fastening. In order to adapt the position of the holding clamp to the length of the stockings, the range of adjustability of the elastic bands must be correspondingly large. Consequently the elastic bands must be of greater length.

This invention relates to an arrangement, according to which the adaptation of the position of the suspender holding clamp relative to the actual length of the stocking is effected owing to a novel construction and movable arrangement of the holding clamp parts. The characteristic feature of the invention consists in that the cooperating clamping means are shiftably and fixably arranged on a narrow band. The band is then fixed in turn to the corset, suspender, belt or the like in a suitable manner.

The advantage attained according to the invention consists substantially in a considerable saving in wide elastic band. This saving is of considerable economical importance as the elastic band is comparatively expensive. A further advantage is, that the narrow band shows less under the clothing than the wide double elastic band. Further fewer metal fastening parts are employed. Thus, a further saving in expenses is obtained. The reduction of the metal parts is also preferred by the wearer, as the suspenders are consequently not so troublesome.

The construction of the cooperating clamping parts may be selected as desired according to the invention. As a rule the one part is formed by the known button, whereas the

other part may be a metal loop, fixed on a shiftable and fixable slide. The metal loop may be rigidly connected to the clamping bar of the slide or oscillatably mounted on a bar provided on the clamping bar. 50

A band with a buttonhole may be substituted for the metal loop.

The metal loop may be arranged on a part formed of two resilient or hingedly connected arms, the one arm having slots for inserting the band and both arms having oppositely situated recesses and projections for clamping the band, whereas the arms are held in the locking position by means of a slide. 55

The button, serving as counter element for the metal loop, is shiftably fixed on the band by means of a slotted plate so that the button can be adapted to the actual position of the metal loop.

Consequently, according to the invention, 60 besides a considerable shortening of the elastic band, only a spring clamping fastening is necessary for the metal loop, whereas in the known constructions a spring clamping fastening for the elastic band and also a fastening eye for the metal loop and further a band fastening for the button were necessary. 65 70

Two embodiments of the invention are illustrated by way of example in the accompanying drawings, in which:

Fig. 1 shows the stocking suspended open for shifting.

Fig. 2 shows the suspender in use.

Figs. 3 to 5 show a further form of construction of the suspender in open position 80 for shifting and in position for use.

For attaching the stocking suspender a narrow band 1 is provided, which is arranged on a short elastic band 2 on the edge 3 of a corset, belt or the like. The band 1 is preferably in the form of a loop, the lower portion of the band serving for covering the metal parts relative to the body. The stocking holding device consists of a metal loop 4, oscillatably attached to a slide 5. The metal 85 90

loop 4 has a web 6, by means of which the band 1 is clamped when the loop 4 is lowered. The metal loop 4 can consequently, when it is in the lifted position, be shifted as desired, on the band 1 and consequently brought 5 into the position required for the actual length of the stocking. At the same time the button 7 for the fastening of the stocking is shiftable on the band 1 in that the button 7 has a base plate 9, provided with two slots 8 10 for pulling through the band. The button can thus be brought into the proper position relative to the loop 4.

According to Figs. 3 to 5 the slide of the 15 metal loop 4 is formed by two resilient arms 10. The band 1 being inserted through a slot 11 in the upper arm 10a so that it comes to lie between both arms. The metal loop 4 is arranged on the upper arm 10a and may be 20 rigidly connected to this arm 10a or hingedly connected thereto. In the arms 10 and 10a oppositely situated projections 12 and recesses 13 are provided, and on the upper arm 10a raised, preferably wedge-shaped webs 14 25 are arranged. By means of a slide 15, which can be shifted over the resilient arms 10, 10a, these latter are pressed together so that the band 1 is pressed by the projections 12 into the recesses 13. Thus, a secure fastening of the 30 loop parts on the band is secured.

The corresponding button 7 is shiftably arranged in the manner already described.

I claim:

1. A stocking suspender, comprising in 35 combination an attaching band, a metal loop, and a button independently shiftable and fixable on said band, and a slide shiftable and fixable on said band connected to said loop.

2. A stocking suspender as specified in 40 claim 1, comprising in combination with the attaching band and the metal loop, a base plate carrying said loop, and an angularly bent projection of said loop adapted to clamp said band against said base plate when said loop is in lowered position.

45 3. A stocking suspender as specified in claim 1, comprising in combination with the attaching band and the metal loop, two resilient arms forming a base plate shiftably mounted on said band and rigidly connected to said loop, and a slide adapted to press together said arms.

50 4. A stocking suspender as specified in claim 1, comprising in combination with the attaching band and the metal loop, two resilient arms forming a base plate shiftably mounted on said band and hingedly connected to said loop, and a slide adapted to press together said arms.

55 5. A stocking suspender as specified in claim 1, comprising in combination with the attaching band and the metal loop, two resilient arms forming a base plate carrying said loop and having opposite projections and recesses adapted to clamp said band.

6. A stocking suspender as specified in claim 1, comprising in combination with the attaching band and the metal loop, two resilient arms forming a base plate carrying said loop, wedge shaped bars on one of said arms, and a slide adapted to engage said bars and press together said two arms onto said band.

In testimony whereof I affix my signature.

WILHELM GREINEISEN.
